UNITED STATES PATENT OFFICE.

FRANK J. KUTSCHER, OF DALLAS, TEXAS, ASSIGNOR TO F. & P. HEEL HOLDER COMPANY, OF DALLAS, TEXAS, A CORPORATION OF TEXAS.

SHOE-HEEL HOLDER.

Application filed July 23, 1928. Serial No. 294,905.

This invention relates to new and useful improvements in shoe heel holders.

One object of the invention is to provide means for applying a heel to a shoe where-
5 by the heel may be securely held to the shoe so that it can be fastened to the shoe prop-
erly and without loss of time.

Another object of the invention is to pro-
10 vide a device whereby a heel may be correct-
ly positioned and firmly held on the shoe,
thus eliminating the necessity of gluing the
heel to the shoe or holding it by hand.

A still further object of the invention is
15 to provide a mechanical means that will re-
duce the labor cost of manufacturing or re-
pairing shoes as a considerable amount of
time is lost in properly fastening heels to
shoes by the crude methods now employed.

A construction designed to carry out the
20 invention will be hereinafter described, to-
gether with other features of the invention.

The invention will be more readily under-
stood from a reading of the following speci-
25 fication and by reference to the accompany-
ing drawings, in which an example of the
invention is shown, and wherein:

Fig. 1 is an elevation showing a shoe
mounted on a last and the heel held in position
30 thereon by a device constructed in ac-
cordance with my invention, portions being
shown in elevation and portions in section,

Fig. 2 is a plan view of the same, the heel
being shown in section,

Fig. 3 is a partial view of the holder and
35 the shoe showing the parts inverted and
ready for nailing on the heel,

Fig. 4 is a detail showing portions of the
holder in section, and

Fig. 5 is a detail showing the bridle bar
40 latch.

In the drawings the numeral 10 designates
a last plate from the sides of which integral
U-shaped supporting members 11 extend.
The members are offset from the plate so as
45 to receive the counter of the shoe when the
last plate is inserted therein, as is shown in
Fig. 1. A yoke 12 is pivoted to the outer
ends of the members 11. An inclined stir-
rup 13 embraces the members 11 and extends
50 upwardly on each side and above the plate
10. The stirrup lies between the yoke and
the members 11.

A saddle loop 14 is suitably fastened to
the forward ends of the yoke and has an off-

set saddle 15 receiving a cushion or pad 16, 55
which may be made of rubber or any other
suitable material. The saddle loop is so lo-
cated that its cushion 16 may be engaged
with the back of the shoe heel when the plate
10 is resting against the inner sole of the 60
shoe.

A handle lever 17 extends forwardly from
one side of the yoke 12 and is bent laterally
so as to be conveniently grasped. A latch
bar 18 is pivoted to the side of the lever and 65
overlies the yoke. This bar is provided with
a pin 19 penetrating the yoke and engaging
an aperture in one of the members 11, where-
by the saddle loop and stirrup are held in
place. The latch bar has a handle 21, and 70
a coiled spring 22 placed between the han-
dle 21 and the lever 17 acts to urge the pin
19 into the aperture 20.

A bridle bar 23 is pivoted to one end of
the stirrup 13 and engages in an aperture 24 75
in the opposite end of the stirrup which is
extended for this purpose. By springing the
extended end of the stirrup to one side, as is
shown in dotted lines in Fig. 5, the bar 23
is freed and may be swung toward and from 80
the heel. An adjusting screw 25 having a
head 26 is mounted in the bar and has a clip
27 swiveled on its lower end. A transverse
cushion 28 similar to the cushion 16 is held
in the clip so as to engage the front side 85
of the heel. It is pointed out that the cush-
ions 16 and 28, while firmly engaging the
heel, prevent injury to the finish thereof.

In using the holder the handle 21 is de-
pressed to swing the bar 18 on lever 17 and 90
withdraw the pin 19 from the aperture 20,
whereby said lever may be swung to spread
the upper ends of the saddle loop 14 and
the stirrup 13. The last plate 10 is then
inserted in the shoe A, the counter being 95
received in the U-shaped member 11, as is
shown in Fig. 1.

The shoe A is then placed upon the usual
last B, as is shown in Fig. 1, and the heel C
is then positioned upon the shoe. After this 100
is done the lever 17 is swung so that the pin
19 rides into the aperture 20. This brings
the cushion 16 into engagement with the rear
side of the heel and the screw 25 may then
be manipulated to bring the cushion 28 into
105 engagement with the front side of the heel.
In some instances it may be necessary to
release the bar 23 and swing it outwardly in

order to place the heel, after which the bar is closed and fastened.

The heel may be firmly clamped and the screw 25 permits a fine adjustment of the heel before the cushion 28 is finally clamped in position. The heel will be firmly held and after being correctly located the shoe A is removed from the last B and inverted, as shown in Fig. 3. The plate 10 is provided with an opening 10' through which the nails may be driven to permanently secure the heel in place. After the heel has been fastened, the lever 17 and the bar 23 are disengaged so as to release the holder from the shoe.

Various changes in the size and shape of the different parts, as well as modifications and alterations, may be made within the scope of the appended claims.

20 What I claim, is:

1. In a heel holding device, a support, a last plate thereon adapted to engage the inner sole of a shoe, a yoke pivoted upon the support, a saddle upon the yoke having means to engage one side of a heel, a stirrup upon the support, and means upon the stirrup to adjustably engage the opposite side of a heel.

2. In a heel holding device, a support, a last plate thereon adapted to engage the inner sole of a shoe, a yoke pivoted upon the support, a saddle upon the yoke having means to engage one side of a heel, a stirrup upon the support, means upon the stirrup to adjustably engage the opposite side of a heel, and a latch upon the yoke detachably engaging the support.

3. In a heel holding device, a support, a last plate thereon adapted to engage the inner sole of a shoe, a yoke pivoted upon the support, a saddle upon the yoke having means to engage one side of a heel, a stirrup upon the support, means upon the stirrup to adjustably engage the opposite side of a heel, a lever arm on the yoke, and a latch lever pivoted upon said arm and having a

projection adapted to extend through the yoke and support.

4. In a heel holding device, a support, a last plate thereon adapted to engage the inner sole of a shoe, a yoke pivoted upon the support, a saddle upon the yoke having means to engage one side of a heel, a stirrup upon the support, a bridle bar pivoted at one side of the stirrup and detachably connected to the opposite side thereof, and a pressure head adjustably mounted on said bar.

5. In a heel holding device, an arched support, a last plate fixed at one end thereof, a yoke pivoted at the opposite end of the support, a fixed saddle extending from the yoke toward its pivot to engage the rear of a shoe heel, a fixed stirrup from the support at an angle to the yoke, and means carried by the stirrup for adjustably engaging the front of said heel.

6. In a heel holding device, a support, a last plate carried by the support, a yoke pivoted on the support, a lever for swinging the yoke, a stirrup rigidly carried by the support and having adjustable means for engaging one side of a heel, and a saddle loop having a saddle for engaging the other side of the heel and carried by the yoke.

7. In a heel holding device, a last plate, U-shaped supporting members extending from the plate for engaging over the heel portion of a shoe, a yoke pivoted to the said members, a lever carried by the yoke, a latch carried by the lever, a stirrup extending from the supporting members, a bridle bar mounted on the stirrup, a cushion member adjustably mounted on the bridle bar, a saddle loop carried by the yoke and having a saddle provided with a cushion, whereby a shoe heel may be held between said cushions.

In testimony whereof I affix my signature.

FRANK J. KUTSCHER.
